CLOSURE AND DISPENSING CAP FOR THE
NECK OF A CONTAINERAlvin J. Porter, Excelsior, Minn., assignor to Product
Design & Engineering, Inc., Minneapolis, Minn.
Filed Mar. 12, 1964, Ser. No. 351,350
7 Claims. (Cl. 222—521)

The invention relates to an improvement in a cap for a container, the cap allowing closure of the container and also dispensing of material therefrom.

It is an object to provide a cap having a base portion with an overcap portion threadedly engaged thereto, the overcap portion carrying a lug adapted to bypass stop means within the base portion which is yieldable in the direction the overcap portion is rotated to threadedly engage the same on the base, the stop means having a construction for engagement with the lug which prevents removal of the overcap portion when the same is rotated in the opposite direction for dispensing the construction allowing easy assembly of the cap and a maintaining of the overcap portion captive on the base portion.

It will not be here attempted to set forth and indicate all of the various objects and advantages incident to the invention, but other objects and advantages will be referred to in or else will become apparent from that which follows.

The invention will appear more clearly from the following detailed description when taken in connection with the accompanying drawings, showing by way of example a preferred embodiment of the inventive idea wherein like numerals refer to like parts throughout.

In the drawings forming part of this application:

FIGURE 1 is a perspective view of the cap in position on a container with the overcap portion in captive position on the base portion, a portion of the container being broken away.

FIGURE 2 is a section on the line 2—2 of FIGURE 1 showing the cap in a closed position.

FIGURE 3 is a section similar to FIGURE 2 with the cap in an open position.

FIGURE 4 is a section on the line 4—4 of FIGURE 3.

FIGURE 5 is a vertical section through the overcap portion removed from the base portion.

FIGURE 6 is a bottom plan view of the overcap portion.

FIGURE 7 is a top plan view of the base portion.

FIGURE 8 is a perspective view of the cap mounted on a container, portions of the cap and container being broken away.

Referring to the drawings in detail, the cap A includes the base portion 10 which is connected to the neck 12 of a container B. The base portion 10 includes the outer hollow cylindrical portion 14 having formed on the outer surface thereof the threads 16. Extending inwardly of the lower end of the cylindrical portion 14 and normal to the longitudinal axis thereof is the narrow annular wall portion 18 which terminates at its inner edge in the inner axial hollow nozzle 20 thereby forming a first annular channel 19 between the portion 14 and the nozzle 20. The upper end of the nozzle 20 is formed with the transverse bar portion 22 which bisects the upper open end of the nozzle thereby forming flow passages 17 and 21. The bar portion includes the upper inverted V-shaped portion 24 which terminates at its apex in the axial closure tip 26.

Further provided are the spaced stops 28 and 30 which are yieldable, for the same are formed of plastic. The stops may be formed of other resilient material or construction. The stop 28 is formed on the outer surface of the nozzle 20 and extends upwardly from the wall portion 18. The stop 28 includes the inclined ramp portion 32

2

which terminates at its greatest thickness in the shoulder stop edge 34. The companion stop 30 is formed on the inner surface of the outer cylindrical portion 14 extending upwardly from the wall portion 18 in juxtaposition to stop 28. The stop 30 includes the inclined ramp portion 36 which terminates at its greatest thickness or rise in the shoulder stop edge 38.

The numeral 40 designates an overcap including the outer cylindrical wall portion 42 which forms an annular apron and which terminates at the upper edge thereof in the circular top portion 44 having the concave formation 46 and the axial outlet hole 48.

Depending from the top portion 44 is the inner cylindrical wall 50 concentric with and spaced from the outer wall 42, and formed on the inner surface of the inner wall 50 are the threads 52 which are engaged with the threads 16 of the portion 14 of the base portion 10 as hereinafter described:

Also depending from the top portion 44 is the collar portion 54 which is spaced inwardly of the inner wall 50 and concentric thereof thereby forming an annular channel 51 between the wall 50 and collar 54. The outer diameter of the collar 54 is substantially equal to the inner diameter of the outer cylindrical portion 14 of the base 10. The inner diameter of the collar 54 is substantially equal to the outer diameter of the hollow nozzle 20 whereby the collar 54 fits snugly in the annular channel 21 to make a sealing engagement between collar 54, nozzle 20 and cylindrical portion 14 but free enough to allow rotation of the collar in the channel as hereinafter described. The depth of the collar 54 and the upper extent of the nozzle 20 is such that the collar remains in contact with the nozzle 20 at all times even in the raised or open position of the overcap 40 upon the base as will be seen particularly in FIGURE 3.

The collar 54 terminates at its inner upper end in the truncated cone formation 55 which terminates in the outlet hole 48. Extending downwardly from the lower edge of the collar 54 and into the channel 21 is the extension 56 in the form of an arcuate lug which is tapered to its forward end 58. The width of the lug 56 at its rear or base end 60 is greater than the distance between stops 28 and 30 at the greatest thickness thereof. The tapered forward end of the lug 56 aids in entry of the lug between the stops 28 and 30 and forced passage therebetween.

The cap is assembled and operated in the following manner: The overcap 40 is positioned on and in axial alignment with the base 10 with the lug 56 extending partially into the channel 19. The overcap is then rotated whereby the threads 52 of the overcap engage the threads 16 of the base portion 10. As the overcap is rotated clockwise and the threads progressively engage the overcap, the same is, of course, drawn down upon the base 10, and as it progresses the lug 56 comes to the stops 28 and 30. With further rotation of the overcap the lug 56 is forced through the restricted passageway between the stops to a point past the stops. The stops 28 and 30 are yieldable as is the lug, inasmuch as the same are plastic and the portions on which the same are mounted are plastic.

With the lug 56 forced to a point just beyond the stops 28 and 30, as illustrated particularly in FIGURE 4, the overcap cannot be rotated from that point in an opposite or counterclockwise direction due to the base end 60 of the lug contacting the stop edges 34 and 38 of the stops 28 and 30. The overcap is now captive upon the base portion 10, and in this position the overcap is not screwed down fully upon the base whereby the closure pin 26 is not within the outlet hole 48 thus leaving the cap in an "open" position whereby the contents of the container

B may flow through the core 20, the passages 19 and 21, and outlet hole 48. The cap is "closed" by rotating the overcap 40 in a clockwise direction whereby the same is drawn down further upon the base 10 by the threads provided and the closure tip 26 enters the outlet hole 48. Again, the cap is placed in an "open" position by rotating the overcap 40 counterclockwise until the lug 56 strikes the stops 28 and 30 and as a result the tip 26 is withdrawn from the outlet hole 48. The lower extent of the lug 56 is such that the lower edge thereof does not contact the wall 18 when the cap is in the "closed" position nor does it escape the stops 28 and 30 when in the upper "open" position.

The invention is not to be understood as restricted to the details set forth since these may be modified within the scope of the appended claims without departing from the spirit and scope of the invention.

Having thus described the invention, what is claimed as new and desired to be secured by Letters Patent is:

1. A closure and dispensing cap for a container comprising:

- (a) a base including,
- (b) an outer hollow cylindrical portion having,
- (c) threads formed on the outer surface thereof,
- (d) a hollow open-ended nozzle secured axially within 25 said outer hollow cylindrical portion and spaced therefrom to form
- (e) a first annular channel surrounding said nozzle,
- (f) a first yieldable stop means formed on the outer surface of said nozzle and extending into said first 30 channel,
- (g) a second yieldable stop means formed on the inner surface of said outer hollow cylindrical portion and extending into said first channel, said second stop means spaced radially from said first stop means, 35
- (h) an overcap including a circular top portion,
- (i) an inner cylindrical wall depending from said top portion,
- (j) said inner cylindrical wall having threads formed 40 on the inner surface thereof adapted to engage the threads of said outer hollow cylindrical portion of said base,
- (k) a collar depending from said top portion concentric with said inner cylindrical wall and into which said nozzle extends for sealing engagement with said nozzle,
- (l) said collar spaced from said inner cylindrical wall 45 thereby forming a second annular channel into which said outer hollow cylindrical portion extends,
- (m) said top portion having an outlet hole formed 50 axially therethrough and communicating internally of said collar,
- (n) said nozzle having a closure tip mounted axially at the upper open end thereof and adapted to extend into said outlet hole when said overcap is screwed upon said base cylindrical portion and close off said outlet hole,
- (o) said collar having a tapered arcuate lug depending therefrom and extending into said first annular channel adapted to be forcibly passed over said first and second yieldable stop means and moved from the same upon threaded rotative movement of said overcap in one direction, movement of said overcap in the opposite direction being prevented by said lug 60 contacting said stop means, said closure tip being withdrawn from said outlet hole when said lug contacts said stop means, said tip being positioned in said outlet hole when said lug is rotatively moved from said stop means, said overcap remaining in threaded engagement with said base portion thereby maintaining the overcap captive on the base.

2. A closure and dispensing cap for a container comprising:

- (a) a base including,
- (b) an outer hollow cylindrical portion having,

- (c) threads formed on the outer surface thereof,
  - (d) a hollow open-ended nozzle secured axially within 10 said outer hollow cylindrical portion and spaced therefrom to form
  - (e) a first annular channel surrounding said nozzle,
  - (f) stop means positioned within said first channel,
  - (g) an overcap including a circular top portion,
  - (h) cylindrical wall depending from said top portion,
  - (i) said cylindrical wall having threads formed on the inner surface thereof adapted to engage the threads of said outer hollow cylindrical portion of said base,
  - (j) a collar depending from said top portion concentric with said cylindrical wall and into which said nozzle extends for sealing engagement with said nozzle,
  - (k) said collar spaced from said cylindrical wall thereby forming a second annular channel into which said outer hollow cylindrical portion extends,
  - (l) said top portion having an outlet hole formed axially therethrough and communicating internally of said collar,
  - (m) said nozzle having a closure tip mounted axially at the upper open end thereof and adapted to extend into said outlet hole when said overcap is screwed upon said base cylindrical portion and close off said outlet hole,
  - (n) said collar having a lug depending therefrom and extending into said first annular channel adapted to be forcibly passed over said stop means and moved from the same upon threaded rotative movement of said overcap in one direction, movement of said overcap in the opposite direction being prevented by said lug contacting said stop means, said closure tip being withdrawn from said outlet hole when said lug contacts said stop means and positioned in said outlet hole when said lug is rotatively moved from said stop means, said overcap remaining in threaded engagement with said base portion thereby maintaining the overcap captive on the base.
3. A closure and dispensing cap for a container comprising:
- (a) a base including,
  - (b) an outer hollow cylindrical portion having,
  - (c) threads formed on the outer surface thereof,
  - (d) a hollow open-ended nozzle secured axially within 40 said outer hollow cylindrical portion and spaced therefrom to form
  - (e) a first annular channel surrounding said nozzle,
  - (f) yieldable stop means positioned within said first channel,
  - (g) an overcap including a circular top portion,
  - (h) a cylindrical wall depending from said top portion,
  - (i) said cylindrical wall having threads formed on the inner surface thereof adapted to engage the threads of said outer hollow cylindrical portion of said base,
  - (j) a collar depending from said top portion concentric with said cylindrical wall and into which said nozzle extends for sealing engagement with said nozzle,
  - (k) said collar spaced from said cylindrical wall thereby forming a second annular channel into which said outer hollow cylindrical portion extends,
  - (l) said top portion having an outlet hole formed axially therethrough and communicating internally of said collar,
  - (m) said nozzle having a closure tip mounted axially at the upper open end thereof and adapted to extend into said outlet hole when said overcap is screwed upon said base cylindrical portion and close off said outlet hole,
  - (n) said collar having a tapered arcuate lug depending therefrom and extending into said first annular channel adapted to be forcibly passed over said yieldable stop means and moved from the same upon threaded rotative movement of said overcap in one direction, movement of said overcap in the opposite direction being prevented by said lug contacting said stop

means, said closure tip being withdrawn from said outlet hole when said lug contacts said stop means and positioned in said outlet hole when said lug is rotatively moved from said stop means, said overcap remaining in threaded engagement with said base portion thereby maintaining the overcap captive on the base.

4. A closure and dispensing cap for a container comprising:

- (a) a base including,
- (b) an outer hollow cylindrical portion having,
- (c) threads formed on the outer surface thereof,
- (d) a hollow open-ended nozzle secured axially within said outer hollow cylindrical portion spaced therefrom to form
- (e) a first annular channel surrounding said nozzle,
- (f) a first yieldable stop member formed on the outer surface of said nozzle and extending into said first channel,
- (g) said first stop having a ramp portion terminating in a stop shoulder,
- (h) a second yieldable stop member formed on the inner surface of said outer hollow cylindrical portion and extending into said first channel,
- (i) said second stop having a ramp portion terminating in a stop shoulder,
- (j) an overcap including a circular top portion,
- (k) a cylindrical wall depending from said top portion,
- (l) said cylindrical wall having threads formed on the inner surface thereof adapted to engage the threads of said outer hollow cylindrical portion of said base,
- (m) a collar depending from said top portion concentric with said cylindrical wall and into which said nozzle extends from sealing engagement with said nozzle,
- (n) said collar spaced from said cylindrical wall thereby forming a second annular channel into which said hollow cylindrical portion extends,
- (o) said top portion having an outlet hole formed axially therethrough and communicating internally of said collar,
- (p) said nozzle having a closure tip mounted axially at the upper open end thereof and adapted to extend into said outlet hole when said overcap is screwed upon said base cylindrical portion and close off said outlet hole,
- (q) said collar having a tapered lug depending therefrom and extending into said first annular channel adapted to be forcibly passed over said yieldable stop members and moved from the same upon threaded rotative movement of said overcap in one direction, movement of said overcap in the opposite direction being prevented by said lug contacting said stop means, said closure tip being withdrawn from said outlet hole when said lug contacts said stop means and positioned in said outlet hole when said lug is rotatively moved from said stop means, said overcap remaining in threaded engagement with said base portion thereby maintaining the overcap captive on the base.

5. A closure and dispensing cap for a container comprising:

- (a) a base including,
- (b) an outer hollow cylindrical portion,
- (c) a hollow nozzle open at both ends and secured axially within said hollow cylindrical portion,
- (d) said nozzle spaced from said outer hollow cylindrical portion thereby forming an annular channel surrounding said nozzle,
- (e) stop means positioned within said channel,
- (f) an overcap including a circular top portion,
- (g) a collar depending from said top portion concentric with said circular top portion and positioned within said channel,

- (h) means threadedly engaging said overcap with said base,
- (i) said top portion having an outlet hole formed axially therethrough,
- (j) said nozzle having a closure tip mounted axially at the upper open end thereof and adapted to extend into said outlet hole and close off the same when said overcap is screwed upon said base,
- (k) said collar having a lug depending therefrom and extending into said annular channel adapted to be forcibly passed over said stop means and moved from the same upon threaded rotative movement of said overcap in one direction, movement of said overcap in the opposite direction being prevented by said lug contacting said stop means, said closure tip being withdrawn from said outlet hole when said lug contacts said stop means and positioned in said outlet hole when said lug is rotatively moved from said stop means, said overcap remaining in threaded engagement with said base portion thereby maintaining the overcap captive on the base.

6. A closure and dispensing cap for a container comprising:

- (a) a base including an outer hollow cylindrical portion formed thereon,
  - (b) a hollow nozzle open at both ends and secured axially within said hollow cylindrical portion,
  - (c) said nozzle spaced from said hollow cylindrical portion thereby forming an annular channel surrounding said nozzle,
  - (d) stop means positioned within said channel,
  - (e) an overcap including a circular top portion,
  - (f) means threadedly engaging said overcap to said base,
  - (g) said top portion having an outlet hole formed axially thereof,
  - (h) said nozzle having a closure tip mounted axially at the upper end thereof and adapted to extend into said outlet hole and close off the same when said overcap is screwed upon said base,
  - (i) said top portion having an extension depending therefrom and extending into said annular channel adapted to be forcibly passed over said stop means upon threaded rotative movement of said overcap in one direction, said lug means abutting said stop means upon threaded rotative movement of said overcap in the opposite direction, said closure tip withdrawn from said outlet hole when said lug means abuts said stop means and positioned in said outlet hole when said lug means is rotatively moved from said stop means, said overcap remaining in threaded engagement with said base portion thereby maintaining the overcap captive on the base.
7. A closure cap for a container comprising:
- (a) a base including an outer hollow cylindrical portion formed thereon,
  - (b) a hollow nozzle open at both ends and secured axially within said hollow cylindrical portion,
  - (c) said nozzle spaced from said hollow cylindrical portion thereby forming an annular channel surrounding said nozzle,
  - (d) stop means positioned within said channel,
  - (e) an overcap including a circular top portion,
  - (f) means engaging said overcap with said base for axial movement thereon,
  - (g) said top portion having an outlet hole formed axially thereof,
  - (h) said nozzle having a closure tip mounted axially at the upper end thereof and adapted to extend into said outlet hole and close off the same when said overcap is fully engaged with said base,
  - (i) said top portion having an extension depending therefrom and extending into said channel adapted to be forcibly passed over said stop means upon rotative movement of said overcap in one direction, said

extension abutting said stop means upon rotative movement of said overcap in the opposite direction, said closure tip withdrawn from said outlet hole when said extension abuts said stop means and positioned in said outlet hole when said extension is rotatively moved from said stop means.
